PADLOCK

Luther Palmer, Hayfork, Calif.

Application June 30, 1952, Serial No. 296,304

4 Claims. (Cl. 70—38)

1
This invention relates to a novel padlock of extremely simple construction capable of being economically manufactured and which will be particularly durable and efficient in use.

More particularly, it is an aim of the invention to provide a padlock wherein both legs of the shackle are engaged to hold the shackle in a closed position and released by operation of a particularly constructed key in the padlock case to allow the shackle to be spring projected to an open position.

A further object of the invention is to provide a padlock having a plurality of springs for urging each of two shackle retaining bolts to projected positions whereby breakage of any one of the shackle bolt projecting springs will not prevent efficient operation of the padlock.

Still a further object of the invention is to provide a padlock having multiple actuating springs for each of the shackle retaining bolts thereof thereby minimizing the tension required on and the loading of each of the springs to thus materially increase the life of the springs and of the padlock.

Various other objects and advantages of the invention will hereinafter become more apparent from the following description of the drawings, illustrating a presently preferred embodiment thereof, and wherein:

Figure 1 is an elevational view looking toward the front side of the padlock and showing the padlock in a closed or locked position;

Figure 2 is an edge elevational view thereof looking from left to right of Figure 1;

Figure 3 is an enlarged sectional view taken substantially along a plane as indicated by the line 3—3 of Figure 2 showing the internal parts of the padlock in side elevation;

Figure 4 is a view similar to Figure 3 but showing other of the parts in section and showing the padlock in an open or unlocked position;

Figure 5 is a horizontal sectional view through the padlock taken substantially along a plane as indicated by the line 5—5 of Figure 4;

Figure 6 is a longitudinal sectional view of the padlock taken substantially along a plane as indicated by the line 6—6 of Figure 3, and

Figure 7 is a fragmentary longitudinal sectional view taken substantially along a plane as indicated by the line 7—7 of Figure 3.

Referring more specifically to the drawings, the novel padlock in its entirety is designated generally 8 and includes a case, designated generally 9, having a front cover plate 10 which is permanently secured thereto by suitable fasten-

ing means 11 and which is provided with a key receiving opening 12. A pin 13 is fixed to and projects from the inner side of a rear wall 14 of the case 9 and is disposed centrally with respect to the ends and sides of the keyhole 12.

As illustrated in Figures 3 and 4, the case 9 is provided in its interior chamber or cavity 15 with a longitudinally extending partition 16 which is disposed substantially parallel to and adjacent a side wall 17 of the case 9. Two transverse partitions 18 extend between the side wall 17 and partition 16 and are disposed nearer the inner end wall 19 than the outer end wall 20 of the case 9. A shackle 21 has a long leg 22 and a short leg 23. The long leg 22 extends slidably through the end wall 19 and partitions 18 and is slidably guided therein. The said leg 22 is disposed between the side wall 17 and partition 16 and has a pin 24 extending therethrough and outwardly thereof forming a spring stop. The pin 24 is disposed in a portion of the shackle leg 22 which is disposed between the outer end wall 20 and the partition 18, adjacent thereto. An expansion coil spring 25 is disposed on the shackle leg 22 between the pin 24 and its terminal, one end of said spring 25 bearing against the end wall 20 and the other end thereof bearing against the pin 24 for urging the shackle 21 to an open, projected position, as illustrated in Figure 4. The pin 24 also functions as a stop for limiting movement of the shackle to a projected position by engagement with the last mentioned partition 18, as illustrated in Figure 4. A short stem 26 may be fixed 35 to the inner side of the end wall 20 to fit into the end of the spring 25 which engages said end wall to hold the spring in axial alignment with the shackle leg 22.

The chamber 15 contains two spaced substantially parallel partitions 27 and 28 which extend a short distance from the inner end wall 19 and which are disposed nearer the opposite side wall 17a than the side wall 17. A shackle retaining bolt 29 extends slidably through and is guided 45 in the partitions 27 and 28 and has a free end 30 adapted to seat in an opening or recess 31 of the short shackle leg 23 to retain the terminal portion of said shackle leg in a closed or locking position within the case 9, as illustrated 50 in Figure 3. Said end 30 of the bolt 29 is rounded on its upper side to form a cam surface for coaction with a beveled surface 32 of the shackle leg 23 whereby as the shackle leg 23 is moved into the case 9 through an opening 55 33 in the end wall 19, the cam surface 32 will

engage the rounded end or cam surface 30 to retract the bolt 29 so that the opening or recess 31 may assume a position to receive the bolt end 30 when said bolt is again moved to a projected position, as illustrated in Figure 3. The bolt 29 has a head 34 disposed to abut the partition 27 to limit movement of the bolt 29 toward a projected position. A stem 35 projects from the head 34 away from the bolt 29 and toward the partition 16 to provide a support for one end of an expansion coil spring 36 which is mounted thereon and abuts against the head 34 and the opposite end of which seats against the partition 16 around a spring support 37 which projects from said partition.

A second bolt 38, which corresponds structurally to the bolt 29 but which is preferably somewhat longer than said bolt 29, extends through a partition 39 which is disposed between a portion of the partition 16 and the side wall 17a and through the partition 16 into the space between the partitions 18, so that the end 30a of the bolt 38 when in a projected position can engage an opening 40 of the shackle leg 22 when said shackle is in a closed position. A bolt head 34a on the opposite end of the bolt 38 abuts the partition 39 to limit movement of the bolt 38 toward a projected position. A stem 35a extends from the head 34a toward the wall 17a to support one end of an expansion coil spring 36a which abuts the head 34a and the opposite end of which abuts a portion of the wall 17a and is disposed around and supported by a projection 37a, fixed to the inner side of said wall. Thus, the bolts 29 and 30a are projected by the springs 36 and 36a, respectively, in opposite directions toward projected positions for engaging the openings 31 and 40 to retain both legs of the shackle 21 in a locked position in the case 9.

A pin 41 is fixed to the rear wall 14 and projects into the chamber 15 adjacent the longitudinal partition 16. A lever 42 is supported turnably on the pin 41 intermediate of its ends and is disposed between a spacing block 43, through which said pin 41 extends, and a retaining washer 44, secured on the pin 41. The spacing block 43 is disposed against the inner side of the rear wall 14. The lever 42 has an end portion 45 projecting from the intermediate portion thereof which engages the pin 41, toward the bolt 38 and which is provided with a right angularly turned terminal portion 46 which extends toward the front wall 10 and loosely engages in a notch 47 in the intermediate portion of the bolt 38. The lever 42 has an elongated shank 48 extending in the opposite direction from its intermediate portion and which is provided with a concavely arced longitudinal edge 49 which faces toward the pin 13. A pull spring 50 has one end connected to a terminal portion of the lever end 48 and is anchored by an eye 51 at its opposite end to the side wall 17a for urging the lever 42 to swing counterclockwise about the pivot 41, as seen in Figures 3 and 4, for urging the retaining bolt 38 to the left or toward a projected position in engagement with the leg opening 40. A bolt actuating lever 52 is swingably mounted intermediate of its ends in the cavity 15 on a pin 53 which is fixed to and projects inwardly from the rear wall 14 which is disposed between the outer end wall 20 and the bolt stem 35a, and adjacent the latter. The pin 53 extends through a plurality of spacing blocks 54 and 54a which are disposed between the lever 52 and the rear wall 14. Said spacing blocks are also engaged by a pin 55

which may loosely fit the uppermost spacing block 54a to allow a limited swinging movement thereof from its position of Figure 3 toward the side wall 17a. The lever 52 has an end 56 extending from its pivot 53 toward the bolt 29 and which has a laterally extending terminal 57 which projects toward the rear wall 14 and loosely fits a notch 58 of the bolt 29. The lever 52 is held between the spacing block 54a and the front wall 10 by a retaining washer 59 which is mounted on the pivot pin 53. The other longer end 60 of the lever 52 extends from the pin 53 toward the end wall 20 and has a concavely arced inner longitudinal edge 61 which faces the pin 13 and the inner edge 49 of the lever end 48. The lever end 56 is disposed between the front wall 10 and the spring 36a and the lever end 60 is disposed between said front wall 10 and the pull spring 50. A pull spring 62 is anchored at one end to the partition 18 through an aperture 63 therein and is connected at its opposite end to the terminal portion of the lever end 60 for urging the lever 52 to swing on its pivot 53 clockwise as seen in Figures 3 and 4 for urging the bolt 29 toward a projected position and in engagement with the shackle leg opening 31. The adjacent edges 49 and 61 are disposed closer together than the adjacent edges of the spacing blocks 43 and 54 and 54a. The rear wall 14 is provided with a ridge 64 on which a portion of the lever end 45 rests and slides.

A key 65 has a tubular stem portion 66 which fits over the pin 13 and is rotatably disposed thereon and is provided with bits 67 and 68 projecting in opposite directions from the stem 66. The bit 67 is provided with a notch or recess portion 69 for accommodating the inner edge 61 of the lever end 60 and the inner edge of the spacing block 54a and the bit 68 is provided with a smaller notch 70 for spacing the bit 68 from the spacing block 43.

Assuming that the padlock 8 is in a closed or locked position as illustrated in Figure 3, the key stem and bits are inserted through the opening 12 into the case 9 with the stem 66 fitting over the pin 13 and the bit 68 being disposed adjacent the end wall 20. The key is then turned clockwise, as seen in Figure 4, so that the notch 69 of the bit 67 will first engage the lever edge 61 to swing the lever 52 counterclockwise on its pivot 53 to retract the bolt 29 to the left out of engagement with the shackle leg 22. The bit 68 thereafter engages the lever edge 49 to swing the lever 42 clockwise on its pivot 41 to retract the bolt 38 out of engagement with the shackle leg opening 40, whereupon the loaded spring 50 projects the shackle 21 away from the case 9 to its open full line position of Figure 4, in which the shackle 21 may be swung about the leg 22 as an axis to its dotted line position of Figure 4. This movement of the levers 42 and 52 and the bolts 29 and 38 loads the lever springs 50 and 62 and the bolt springs 36 and 36a. Accordingly, when the key is turned in the opposite direction to re-align the bits 67 and 68 with the opening 12, the bolt 29 will return to a projected position and the lever 52 will be returned by the spring 62 to its position of Figure 3. However, the bolt end 30a will remain in engagement with the shackle leg 22 so that said bolt and its actuating lever 42 will still be retained substantially in their positions of Figure 4. When the shackle 21 is thereafter swung back to its full line position of Figure 4 and displaced toward the case 9, the leg 22 will slide inwardly of the case and the

leg 23 will slide through the case opening 33 so that engagement of the cam surfaces 32 and 30, as previously described, will retract the bolt 29 and return the lever 52 to its position of Figure 4. As the shackle 21 reaches a fully closed position, the opening 31 will align with the bolt 29 and the opening 40 will align with the bolt 38 whereupon the bolt 29 and its actuating lever 52 will be moved to their positions of Figure 3 by the combined action of the springs 36 and 62 and the bolt 38 and lever 42 will be moved to their positions of Figure 3 by the combined action of the springs 36a and 50 so that both bolts will be disposed in projected positions to retain the shackle 21 in a closed or locked position. It will thus be readily apparent that the bolt 29 and lever 52 will function should either the spring 36 or 62 break and the bolt 38 and lever 42 will likewise function as previously described should either the spring 36a or 50 break.

Various modifications and changes are contemplated and may obviously be resorted to, without departing from the spirit or scope of the invention as hereinafter defined by the appended claims.

I claim as my invention:

1. A padlock of the character described comprising a case, a shackle having a shorter leg and a longer leg, said longer shackle leg being slidably and nondetachably mounted in said case, said shorter leg being slidably movable into one end of said case and outwardly thereof for disengaging the shorter shackle leg from the case when the lock is in an open or unlocked position, said shackle legs each being provided with a bolt receiving recess, a pair of bolts reciprocably mounted in said case transversely of the shackle legs, bolt springs individual to said bolts for urging the bolts in opposite directions toward projected positions in engagement with the shackle leg recesses for latching both of the shackle legs within the case, a pair of bolt actuating levers individual to said bolts pivotally mounted intermediate of their ends in the case and having complementary bolt engaging terminal portions, said bolts having notches loosely engaged by said terminal portions, said levers having opposite complementary ends laterally spaced relatively to one another and disposed on the opposite sides of the lever pivots to the first mentioned lever ends, said last mentioned lever ends forming key engaging portions and defining a key receiving space therebetween, said key engaging lever ends being adapted to be swung away from one another by the turning movement of a key disposed in the key receiving space for rocking the levers in opposite directions to move the bolts in opposite directions toward retracted positions out of engagement with the keeper recesses of the shackle legs whereby the shackle is released for movement outwardly of the case to an unlocked open position, and pull springs individual to the levers, said pull springs being anchored to the case and connected with the last mentioned lever ends for urging said levers to swing in opposite directions for displacing the bolts toward projected positions, each of said bolts and the lever engaged thereby being actuated by the respective bolt spring and pull spring, and each of said springs being capable of moving the bolt to a projected position and rocking the lever engaging said bolt to a position to be actuated by the key.

2. A padlock of the character described com-

prising a case, a shackle having a shorter leg and a longer leg, said longer shackle leg being slidably and nondetachably mounted in said case, said shorter leg being slidably movable into one end of said case and outwardly thereof for disengaging the shorter shackle leg from the case when the lock is in an open or unlocked position, said shackle legs each being provided with a bolt receiving recess, a pair of bolts reciprocably mounted in said case transversely of the shackle legs, bolt springs individual to said bolts for urging the bolts in opposite directions toward projected positions in engagement with the shackle leg recesses for latching both of the shackle legs within the case, a pair of bolt actuating levers individual to said bolts pivotally mounted intermediate of their ends in the case and having complementary bolt engaging terminal portions, said bolts having notches loosely engaged by said terminal portions, said levers having opposite complementary ends laterally spaced relatively to one another and disposed on the opposite sides of the lever pivots to the first mentioned lever ends, said last mentioned lever ends forming key engaging portions and defining a key receiving space therebetween, said key engaging lever ends being adapted to be swung away from one another by the turning movement of a key disposed in the key receiving space for rocking the levers in opposite directions to move the bolts in opposite directions toward retracted positions out of engagement with the keeper recesses of the shackle legs whereby the shackle is released for movement outwardly of the case to an unlocked open position, and spacing blocks interposed between a wall of the case and one of said levers for offsetting said lever relatively to the other lever and to the bolt engaged by said other lever, the bolt spring of said last mentioned bolt being disposed between said case wall and the lever offset by the spacing blocks.

3. A padlock of the character described comprising a case, a shackle having a shorter leg and a longer leg, said longer shackle leg being slidably and nondetachably mounted in said case, said shorter leg being slidably movable into one end of said case and outwardly thereof for disengaging the shorter shackle leg from the case when the lock is in an open or unlocked position, said shackle legs each being provided with a bolt receiving recess, a pair of bolts reciprocably mounted in said case transversely of the shackle legs, bolt springs individual to said bolts for urging the bolts in opposite directions toward projected positions in engagement with the shackle leg recesses for latching both of the shackle legs within the case, a pair of bolt actuating levers individual to said bolts pivotally mounted intermediate of their ends in the case and having complementary bolt engaging terminal portions, said bolts having notches loosely engaged by said terminal portions, said levers having opposite complementary ends laterally spaced relatively to one another and disposed on the opposite sides of the lever pivots to the first mentioned lever ends, said last mentioned lever ends forming key engaging portions and defining a key receiving space therebetween, said key engaging lever ends being adapted to be swung away from one another by the turning movement of a key disposed in the key receiving space for rocking the levers in opposite directions to move the bolts in opposite directions toward retracted positions out of engagement with the keeper recesses of the shackle legs whereby the shackle is released for movement outwardly of the case to an unlocked open position, and spacing blocks interposed between a wall of the case and one of said levers for offsetting said lever relatively to the other lever and to the bolt engaged by said other lever, the bolt spring of said last mentioned bolt being disposed between said case wall and the lever offset by the spacing blocks.

4. A padlock of the character described comprising a case, a shackle having a shorter leg and a longer leg, said longer shackle leg being slidably and nondetachably mounted in said case, said shorter leg being slidably movable into one end of said case and outwardly thereof for disengaging the shorter shackle leg from the case when the lock is in an open or unlocked position, said shackle legs each being provided with a bolt receiving recess, a pair of bolts reciprocably mounted in said case transversely of the shackle legs, bolt springs individual to said bolts for urging the bolts in opposite directions toward projected positions in engagement with the shackle leg recesses for latching both of the shackle legs within the case, a pair of bolt actuating levers individual to said bolts pivotally mounted intermediate of their ends in the case and having complementary bolt engaging terminal portions, said bolts having notches loosely engaged by said terminal portions, said levers having opposite complementary ends laterally spaced relatively to one another and disposed on the opposite sides of the lever pivots to the first mentioned lever ends, said last mentioned lever ends forming key engaging portions and defining a key receiving space therebetween, said key engaging lever ends being adapted to be swung away from one another by the turning movement of a key disposed in the key receiving space for rocking the levers in opposite directions to move the bolts in opposite directions toward retracted positions out of engagement with the keeper recesses of the shackle legs whereby the shackle is released for movement outwardly of the case to an unlocked open position, and pull springs individual to the levers, said pull springs being anchored to the case and connected with the last mentioned lever ends for urging said levers to swing in opposite directions for displacing the bolts toward projected positions, each of said bolts and the lever engaged thereby being actuated by the respective bolt spring and pull spring, and each of said springs being capable of moving the bolt to a projected position and rocking the lever engaging said bolt to a position to be actuated by the key.

5. A padlock of the character described com-

recesses of the shackle legs whereby the shackle is released for movement outwardly of the case to an unlocked open position, said last mentioned lever ends having opposed concavely arced longitudinal edges forming cam surfaces adapted to be engaged by bits of the key for rocking the levers in opposite directions to retract the bolts.

4. A padlock as in claim 3, one of said cam edges being disposed nearer the axis of the key than the other cam edge and being initially actuated by turning of the key for retracting the bolt engaged by said lever out of engagement with the shorter shackle leg before the other lever is actuated by the key to retract the other bolt out of engagement with the longer shackle leg.
